UNITED STATES PATENT OFFICE.

WILLIAM J. KAYSER, OF MILWAUKEE, WISCONSIN.

CLOTHES-DRIER.

SPECIFICATION forming part of Letters Patent No. 469,018, dated February 16, 1892.

Application filed October 11, 1890. Serial No. 367,808. (No model.)

To all whom it may concern:

Be it known that I, WILLIAM J. KAYSER, a citizen of the United States, and a resident of Milwaukee, in the county of Milwaukee, 5 and in the State of Wisconsin, have invented certain new and useful Improvements in Clothes-Driers, &c.; and I do hereby declare that the following is a full, clear, and exact description thereof.

10 My invention relates to devices for supporting clothing and other fabrics in proper position for drying after the same have been laundered; and my invention consists in certain peculiar and novel features of construction and arrangement, as will be hereinafter described and claimed.

In the accompanying drawings, Figure 1 is a plan view, partly broken away, of a structure embodying my invention. Fig. 2 is a side 20 elevation of the same. Fig. 3 is a sectional view on the line 3-3 of Fig. 2. Fig. 4 is a detached view of a portion of one of the supporting-arms of the device, showing a number of the line-carriers. Figs. 5, 6, and 7 are 25 separate perspective views of the parts of the apparatus which are located at the top of the post.

The objects of my invention are to produce a structure which shall be simple, durable, 30 and inexpensive in construction and which shall be adapted for a great variety of uses; also to produce a structure which shall economize space, and at the same time be capable of receiving a large number of articles for 35 drying or display, and finally to provide a structure the supporting-arms of which shall be readily variable in position to accord with the requirements of different kinds of articles suspended therefrom. These results I attain 40 by virtue of the construction which I will now proceed to describe.

In the said drawings, A designates the vertical post or support of the device, the upper part only of which is shown, but which is intended to be of any required length or height, 45 as circumstances may suggest. This post is preferably angular in cross-section, and upon its upper end is placed a cap B, which is preferably an integral casting corresponding in 50 form to the post A and having a number of pendent extensions b, each of which is preferably V-shaped, as shown, to embrace the

edges of the post A. This cap is secured in position upon the post A by a number of screws C, which pass through the angles of 55 the extensions b and enter the post A, as is best shown in Fig. 2. The outer portions of these screws protrude horizontally beyond the extensions b, and extend each through the hub of an anti-friction wheel or roller D, 60 the said rollers or wheels being thus in vertical position, as shown. A vertical rod or pin E extends upward from the center of the top of the cap B, and is externally screw-threaded at its upper end to receive an internally- 65 threaded nut F, for a purpose to be presently explained.

Immediately above the cap B is placed a horizontal disk-shaped platform G, which rests upon the rollers or wheels D, and which 70 carries on its upper side a central hollow vertical boss or hub g, through which extends the pin E above described. At its margin this platform carries on its upper side two horizontal sockets g' g', which, together with the boss 75 or hub g, are preferably integral with the said platform. These sockets are preferably square or angular in cross-section and extend radially of the platform at opposite sides of a line drawn longitudinally through the center 80 of the platform. Into each of these sockets g' is inserted the inner end of a horizontal supporting arm or bar H, the two arms thus extending oppositely from each other, as shown in Fig. 1. Midway between the two 85 sockets g' and in the margin of the platform G is formed a notch or recess g², for a purpose to be presently explained.

Immediately above the platform G is located a second platform I, also preferably of 90 disk form and carrying on its under side a central hollow hub or boss i, through which the pin E passes also. At opposite points upon its under side, near the margin thereof and on opposite sides of a line drawn longitudinally through the center of the platform, the latter carries two sockets i' i'. These 95 sockets are preferably square or angular in cross-section, and they, together with the boss i, are preferably integral with the platform I. 100 These sockets i' receive each the inner end of a supporting arm or bar H', the said arms thus extending horizontally and oppositely from each other, as shown in Fig. 1. Midway

between the two sockets i' and at its margin the upper platform I carries a pivoted gravity-dog i^2 , which is designed for engagement with the notch g^2 of the lower platform, as 5 will be presently explained.

It will be seen that the two platforms G and I are held in proper operative relation by the nut F, and that normally the two pairs of arms extend at right angles to each other, as shown 10 in solid lines in Fig. 1. In this position of the parts the dog i^2 is engaged in the notch g^2 and the device is adapted to serve as a clothes-drier, the clothes being suspended from a line attached to the arms H H', preferably in the 15 manner to be hereinafter explained. When, however, heavier articles—such as carpets, outer clothing, or the like—are to be suspended from the arms H H', the dog i^2 is raised out of the notch g^2 and the upper platform 20 is swung around, so that the two pairs of arms shall extend parallel with each other, as indicated in dotted lines in Fig. 1, and in this position the dog i^2 is dropped into a notch g^3 , formed in the margin of platform G, 25 adjacent to one of its sockets g' . The two bars which lie together thus possess unitedly sufficient strength to support heavy articles which could not be supported by one bar alone. To the under side of one of the bars— 30 as, for example, a bar H—is attached a U-shaped spring K, one end of which is secured by two or more screws k, and the opposite end k' of which preferably extends downward and outward, as shown in Fig. 2. Upon the under 35 side of this bar and of the others also are secured in longitudinal alignment a number of cleats L, each of which is of double-L form. On the upper side of each cleat, at the juncture of its two arms, is formed a teat m, which 40 enters a corresponding depression in the under side of the supporting-arm, and through one of the said cleat-arm extends an attaching-screw m' , which enters said supporting-arm. The opposite arm of the cleat is formed on 45 its upper side with a swell or enlargement m^2 . From this construction it will be understood that a knot is formed in one end of a line N and said line is inserted above the bend of spring K, the knot preventing accidental detachment of the line from said spring. The 50 supporting-arms H H' being placed as shown in solid lines in Fig. 1, (with the dog i^2 in the notch g^2 ,) the line is passed successively in volute form or strands over the swells m^2 of cleats 55 L and is held thereby. Thus a great length of line is securely strung in a very compact space and a large number of articles can be suspended compactly for drying.

From the foregoing description it will be 60 seen that the device in either of its adjustments is freely revoluble upon the support-

ing-post, and that it is compact, durable, and simple in construction and readily manipulated.

It is to be observed that the lower platform 65 G extends over the wheels or rollers D, and this relative position of said parts is important, because the said platform thus rests the wheels or rollers against the weather and clogging from ice or snow. 70

By the herein-described arrangement of the rollers upon the outside of the cap and with bearings only at their upper sides against the under side of the platform frictional resistance is very materially decreased, and the 75 device is adapted to rotate more freely about the central pin than if the rollers were arranged to have more than one point of frictional engagement with the other parts of the device. 80

Having thus described my invention, what I claim as new, and desire to secure by Letters Patent, is—

1. An improved device for drying clothes, comprising a supporting-post, a cap-piece covering the same, screws extending through said cap into the post and arranged to project outside of said cap, a platform centrally supported upon said cap and provided with supporting-arms, and anti-friction rollers journaled upon the outer ends of said screws at the outside of said cap and having frictional engagement only at their upper sides with the under surface of the platform, substantially as described. 95

2. An improved device for drying clothes, comprising a number of platforms carrying oppositely-disposed sockets, one of said platforms being marginally notched or recessed, and a dog carried by another platform and 100 engaging the said notches to retain the platforms in different positions of adjustment, substantially as set forth.

3. An improved device for drying clothes, comprising a support, a cap-piece therefor, 105 attaching-screws for the cap-piece, anti-friction rollers supported by said screws, a centering-pin, a number of socket-carrying platforms centered upon said pin, one of said platforms being marginally notched, and a dog 110 carried by another platform and engaging said notches to retain the platforms in different positions of adjustment, substantially as set forth.

In testimony that I claim the foregoing I 115 have hereunto set my hand, at Milwaukee, in the county of Milwaukee, and State of Wisconsin, in the presence of two witnesses.

WILLIAM J. KAYSER.
